UNITED STATES PATENT OFFICE.

WILLIAM H. GAILOR, OF SARATOGA SPRINGS, NEW YORK.

HAME-STRAP.

SPECIFICATION forming part of Letters Patent No. 739,167, dated September 15, 1903.

Application filed March 18, 1903. Serial No. 148,400. (No model.)

To all whom it may concern:

Be it known that I, WILLIAM H. GAILOR, a citizen of the United States, residing at Saratoga Springs, in the county of Saratoga and State of New York, have invented new and useful Improvements in Hame-Straps, of which the following is a specification.

By means of this invention a hame can be readily clasped or freed, as required, and securely held when in use; and this invention in hame strap or fastener resides in certain novel features of construction set forth in the following specification and claims, and illustrated in the annexed drawings, in which—

15 Figure 1 is a sectional edge view of the strap or fastener in engaging position. Fig. 2 is an edge view of Fig. 1, the device being unlocked or in freeing position. Fig. 3 is a section along x x , Fig. 1. Fig. 4 is a plan view of Fig. 2.

In the drawings are shown what may be called a "base-piece" 4 and straps 2 and 3, with a lever 1. These parts when formed of metal are strong and durable and can be made to give a compact structure.

The lever is shown fulcrumed at e to one of the straps, and its fulcrum end is formed into ears or catch portions. When an eye of the hame-wood is slipped onto the lever or 30 handle 1 and the latter swung to the straps or to locking position, such lever will hold itself in place or be locked by the strain on the strap. When swung to freeing position, the eye of the hame-wood is thrown off the hook or ears at the fulcrum end of the lever and can be slipped off the free end of the same.

The strap 2 can be formed from a flat piece of steel and is shown adjustable along base-piece 4. The hook-shaped end portion of this strap or piece 2 forms a bearing for the fulcrum e . A suitable number of eyes or holes—for example, seven—enable the strap 2 to be set along the base-piece for the plugs or studs 45 to slip into various eyes of the strap and hold the same in varying adjustment for shortening or lengthening, as required.

The strap 3 can be formed of hoop-iron and is shown bent double and also perforated—50 as, for example, by seven or other suitable number of holes in—each shank. This strap or loop can be similarly adjusted along base-

piece 4 by having different ones of its eyes slipped over the studs f . These studs when threaded and provided with nuts g will hold 55 the parts connected. Two studs are shown; but this number can be varied.

Directions for use can be worded as follows: Remove both nuts g and remove base 4. The loop or strap 3 can be slipped to engagement with one hame loop or eye. The strap 2 is placed on, the studs to the position required by the user, and strap 3 is also placed thereon, as desired. The nuts being then screwed on, the parts are secured to one 65 another. In placing straps 2 and 3 in position either one may be put on first, or strap 2 can be placed between the shanks or ends of strap 3, as the user may desire. The base-piece 4 being suitably flanged or trough-shaped, the parts when in place are held in alinement.

When the device is secured to one hame-eye, the other hame-eye is slipped over the free end of the lever 1 to the hook or catch 75 part at the fulcrum. The lever is then swung to locking position and carries the hame-eye over the hook end of strap 2, and at the same time such lever automatically snaps and holds itself in locking position as its free end is 80 swung to the straps.

What I claim as new, and desire to secure by Letters Patent, is—

1. A hame-fastener, comprising a flanged base-piece provided with openings, a strap 85 extending between the flanges and the base-piece, provided with a series of openings and carrying on its outer end a catch-lever for connecting a hame thereto, a doubled strap extending between the flanges of said base-piece, said doubled strap provided with a series of openings adapted to register with the openings in the first-mentioned strap and forming a loop for connecting a hame thereto, and means adapted to extend through the 95 openings in the straps and base-piece for fastening said base-piece and straps together.

2. A hame-fastener, comprising a flanged base-piece provided with openings, a strap extending between the flanges of the base-piece, provided with a series of openings and carrying on its outer end a catch-lever for connecting a hame thereto, a doubled strap 100 extending between the flanges of said base-

piece and engaging the upper and lower faces of said first-mentioned strap, said doubled strap provided with a series of openings adapted to register with the openings in the 5 first-mentioned strap and forming a loop for connecting a hame thereto, and means adapted to extend through the openings in the straps and base-piece for fastening said base-piece and straps together.

- 10 3. A hame-fastener, comprising a flanged base-piece provided with openings, a strap extending between the flanges of the base-piece, provided with a series of openings and carrying on its outer end a catch-lever for 15 connecting a hame thereto, a doubled strap extending between the flanges of said base-

piece, said doubled strap provided with a series of openings adapted to register with the openings in the first-mentioned strap and forming a loop for connecting a hame thereto, bolts extending through the openings in the straps and base-piece for adjustably connecting them together, and nuts mounted on said bolts for securing them in position. 20

In testimony whereof I have hereunto set 25 my hand in the presence of two subscribing witnesses.

WILLIAM H. GAILOR.

Witnesses:

FRANK H. McDONALD,
WILLIAM G. FOX.
